BELTING OR THE LIKE

George W. Delano, Detroit, Mich.

Application June 30, 1952, Serial No. 20,420

Term of patent 7 years

(Cl. D3—10)

To all whom it may concern:

Be it known that I, George W. Delano, a citizen of the United States of America and a resident of Detroit, in the county of Wayne and State of Michigan, have invented a new, original, and ornamental Design for a Belting or the like, of which the following is a specification, reference being had therein to the accompanying drawing, forming a part thereof, wherein:

I claim:

The ornamental design for belting or the like, substantially as shown.

GEORGE W. DELANO.
